UNITED STATES PATENT OFFICE

172,100

CONCRETE MIXER

John W. Lendved, Milwaukee, Wis., assignor to Chain Belt Company, Milwaukee, Wis., a corporation of Wisconsin

Application August 3, 1951, Serial No. 16,135

Term of patent 14 years

(Cl. D14—3)

To all whom it may concern:

Be it known that I, John W. Lendved, a citizen of the United States of America, residing at Milwaukee, county of Milwaukee, State of Wisconsin, have invented a new, original, and ornamental Design for a Concrete Mixer, of which the following is a specification, reference being had to the accompanying drawings, forming a part hereof.

In the said drawings:

Fig. 1 is a perspective view of a concrete mixer embodying the new design, taken looking toward the left or operator's side from the discharging end thereof;

Fig. 2 is a perspective view of the mixer looking toward the same side, but from the forward end thereof;

Fig. 3 is another perspective view looking toward the opposite side of the mixer from the discharging end thereof; and

Fig. 4 is a top plan view of the concrete mixer. The dotted lines shown in Fig. 1 are for illustrative purposes only.

I claim:

The ornamental design for a concrete mixer, substantially as shown and described.
